United States Patent

Des. 239,538
Patented Apr. 13, 1976

239,538

LOUDSPEAKER

George R. Wagner, Santa Ana, Calif., assignor to
Altec Corporation, Anaheim, Calif.

Filed Oct. 25, 1974, Ser. No. 518,109

Term of patent 14 years

Int. Cl. D14—01

U.S. Cl. D26—14 G

FIG. 1

FIG. 4

FIG. 2

FIG. 3

FIG. 5

FIG. 1 is a front plan view of a loudspeaker, showing my new design;

FIG. 2 is a rear view of the loudspeaker;

FIG. 3 is a side elevational view of the loudspeaker;

FIG. 4 is a side elevational view of the loudspeaker taken from an angle 90° from the view of FIG. 3; and

FIG. 5 is a perspective view of the loudspeaker taken from the rear thereof.

I claim:

The ornamental design for a loudspeaker, as shown.
